UNITED STATES PATENT OFFICE.

HUBERT NOTEBOOM, OF PHILADELPHIA, PENNSYLVANIA.

PUNCHING DIE.

Application filed April 12, 1924. Serial No. 706,197.

To all whom it may concern:

Be it known that I, HUBERT NOTEBOOM, a citizen of the United States, residing at Philadelphia, in the county of Philadelphia and State of Pennsylvania, have invented new and useful Improvements in Punching Dies, of which the following is a specification.

This invention relates to a punching die, 10 and an object of the invention is to provide a practical punching die structure, primarily designed for use in the making of combs of paper fibre or analogous material, such as disclosed in the application of 15 George G. Sowers, filed September 23rd, 1922, Serial No. D-3813, and adaptable for disclosure in the application for Letters Patent of the United States, filed April 9th, 1924, 20 Serial No. 705,329.

In the manufacture of combs of this type, it is necessary that extreme care and precision be exercised in the punching of the combs so as to prevent the rupturing of 25 the points of the teeth during the punching operation, and to permit the exercising of care in the forming of the combs without material hindrance to speed of production.

The improved punch and die structure 30 herein described, has been conceived, which die includes the suitable opening cut to conform to the configuration of the comb, and it has a stop member located in close proximity to the tooth forming edge of the opening, in the die to permit the regulating of 35 the positioning of the sheet of material, so as to permit speed in the forming of the combs, and ensure precision in the spacing of the material.

40 Other objects of the invention will appear in the following detail description, and in the accompanying drawings wherein:

Figure 1— is a top plan of the die.

Figure 2— is a section through the die 45 taken on the line 2—2 of Figure 1.

Figure 3— is a plan view of the punch.

Figure 4— is a side elevation of the punch used in connection with the die.

Referring more particularly to the drawings, the improved die comprises the block 1 which is formed of sections 2 and 3. The sections 2 and 3 are provided with dowels 4 and semi-cylindrical recesses 5, to permit proper engagement of their inner edges to 50 ensure proper feeding of the sections of the comb forming opening 6, which is cut in

the die block. The opening 6 is shaped to completely form a comb of the type heretofore mentioned, and it has the teeth cutting members 7 disposed along one side 60 thereof, preferably away from the direction in which the material is fed to the punch press. Extreme precision is necessary in feeding material over the die, so as to insure proper formation of the teeth of 65 the comb without rupturing or mutilating the points of the teeth, which mutilation would be caused if a proper body of material was not left in the sheet of material beyond the points of the teeth, and to insure this proper spacing of the material 70 without causing waste of the material, a raised stop 8 is formed centrally on the upper surface of the section 2 of the block 1, a predetermined distance from the tooth 75 forming portion of the die opening 6, so as to permit proper spacing of the material to provide sufficient body between each comb punched without causing a waste of the material. In the drawings only one stop 8 is 80 illustrated, and it is shown as disposed in the transverse center of the block with an abrupt end facing the die opening 8, while its opposite end is rounded.

In passing material over the die block 85 1 for the forming of combs after the first comb has been cut from the strip of material which material is slipped over the die until the straight edge of the back of the opening formed in the material by the cutting of a comb therefrom engages against the stop 8, which ensures proper spacing of 90 the material for the cutting of the subsequent comb, and thus the operation is continued.

In Figures 3 and 4 of the drawings, the punch used in connection with the die block 1 is illustrated, and this punch comprises the rectangular carrying body plate 10, which has the shank 11 thereon and it also 100 has projecting laterally therefrom, one side thereof, a comb-shaped cutter 13, which is shaped to the exact size of the comb to be cut, and for co-operation with the die opening 6. The cutter 13 is relatively thick and the teeth 14 thereon are milled uniformly for a predetermined portion of their length, as clearly shown in Figure 4 of the drawings, after which they materially increase in thickness towards the carrying block 10, 110 thus it will be seen that the teeth 14 on the cutter 13, gradually increase in thickness

from their free edges, transversely towards the main body of the cutter 13, and that they extend longitudinally for a predetermined distance of uniform thickness, after which 5 they gradually incline and increase in thickness towards the carrying block 10, thereby providing not only the proper shape to the comb but sufficient body to the cutter itself, to ensure longevity thereof. The co-operating 10 of the operation of the punch structure and the die structure is of the usual and well-known manner.

It is, of course, to be understood, that the invention may be constructed in various 15 other manners and the parts associated in different relations, and therefore, I do not

desire to be limited in any manner, except as set forth in the claim hereunto appended.

What I claim is:

A comb forming punch comprising a carrying body, a comb-shaped cutter carried thereby having a plurality of comb tooth forming teeth thereon, which gradually increase in thickness from their free edges to the main body of the cutter and are of the uniform thickness at their free edge for a predetermined longitudinal distance after which they gradually increase in thickness towards said carrying body. 20 25

In testimony whereof I affix my signature.

HUBERT NOTEBOOM.
